MACHINE FOR HANDLING CARDS
AND THE LIKEAlbert C. Chew, New York, N. Y., assignor to
Hobson-Miller Machinery, Inc., New York,
N. Y., a corporation of New York

Application April 16, 1952, Serial No. 282,630

4 Claims. (Cl. 271—11)

1

Particularly, but not exclusively, in the printing arts, there are manifold requirements for the economic and high speed handling of stacks of cards and like small paper forms upon which is to be performed some operation such as the printing of written information. The preparation of common postal envelopes of various sizes and shapes is a good example.

In keeping with its general objects, the present invention provides for such usages as the foregoing, new and improved automatically functioning machines which have such prominent advantages as the following with respect to machines hitherto available: greater versatility in the accommodation of different sized cards; and greater reliability against malfunctioning during high speed handling of the successive cards in the stack, whereby each card of the stack may be rapidly processed through the machine with minimum risk of mangling, improper printing, or improper ejection from the machine.

The combinations of elements comprising the invention and which provide the foregoing advantages, as well as others, will better be understood by reference to the following description of one illustrative embodiment. It is to be understood, of course, that numerous modifications of this embodiment may be made without departing from the full scope of the invention. It will be understood further that the illustrated machine is capable of handling many forms of small paper or like stacked objects, whether for printing or other purposes, and that, therefore, the word "card" is chosen for convenience of description and, consequently, is to be construed broadly as meaning any such objects.

In the annexed drawings which show the illustrated embodiment:

Fig. 1 is a side view of the entire machine showing, in general, a rack-like card feed hopper at the top for feeding cards successively to the printing roller mechanism shown to its left, the power mechanisms being below;

Fig. 2 is a top elevational view of Fig. 1 along the lines 2—2;

Fig. 3 is a detailed sectional view along the lines 3—3 of Fig. 2;

Fig. 4 is an illustration of the separator disks for separating the leading cards from the stack immediately before their engagement with the roller, including parts of a finger mechanism which positively pushes the lower edge of the card into engagement with the roller;

Fig. 5 is a detailed illustration of the latter finger mechanism;

2

Fig. 6 illustrates the mechanism for varying the width of the feed hopper to accommodate different width cards;

Fig. 7 is an illustration in better detail, particularly of the reciprocating suction mechanisms which draw the leading cards into engagement with the separator disks and is a view as though along the lines 7—7 of Fig. 3; while

Figs. 8, 9 and 10 are schematic illustrations of the working of the separator disks.

Referring now to the drawings, the general elements of the machine are as follows. For printing purposes, a stack of cards 11 (Fig. 3) is to be placed on an inclined rack-like feed 15 hopper 12 having guide racks 13 and 14 laterally adjustable from the center line (Fig. 2) so as to accommodate different width cards. As the cards move down the rack, the leading card is fed successively to the printing mechanism comprising the pressure roller 15 and the co-operating printing cylinder 16 so that the cards may be passed successively between the roller 15 and the cylinder 16 with the relative rotation of these two members. Additional guide rollers 17 (Fig. 7) resting on the pressure roller 15 and rolling freely thereon by virtue of its own weight and friction is provided for engaging and guiding the upper edge of the cards and facilitating their entry into the space between a fixed curved guide 17a and the roller 15. The pressure roller 15, as best indicated by Fig. 2, takes the form of a cylinder having cut-out portions 18 extending axially inwardly from the ends of its generally cylindrical configuration so as to form peripherally spaced plate-like segments 19 upon which the cards are carried individually during the printing or like processing; the roller structure being supported and made rigid by its narrow central cylindrical strip 20 (Fig. 2), the spokes 21 and the hub 22.

For peeling off or separating the successive leading cards from the stack 11 so that they may be pushed into engagement with the roller 15 by mechanisms presently to be indicated, there are provided the segmented separator disks 23 and 24 positioned so that each may engage one of the two ends of the leading card as best illustrated by the Figs. 4 and 8 through 10. As seen, these disks have a wheel-like form except for the open gaps 25 and 26 in their peripheries leading into the areas between the spokes. In operation, these disks rotate in directions indicated by the arrows in Figs. 4 and 8 through 10 in such manner that their leading edges 27 and 28 may be introduced between the leading card of the stack and its successor, whereby continued rotation

will completely separate the leading card from the stack as one revolution of the disks is completed.

Co-operating with and facilitating the action of the disks 23 and 24 are the air suction mechanisms 29 and 30, i. e., one for each of the disks. Each of these may comprise a suitable flexible hose-like device, such as rubber hoses 31 and 32 arranged to be reciprocated in timed relation by means later to be described in such manner that they will move forward toward the stack 11 and through the cut-out portions 18 into close proximity with the disks 23 and 24 and then move rearwardly at the proper time so as not to interfere with the movement of the segments 19. These mechanisms function to suck the upper corners of the card forwardly to insure unfailing insertion of the leading edges 27 and 28 between the leading card and its successor. The hoses may be supplied with low pressure air for suction by any suitable means (not shown). This action is best illustrated by the Figs. 8, 9 and 10. Fig. 8 illustrates the time at which the hoses 31 and 32 have advanced to their forwardmost position at which they suck forward the upper corners of the card (Fig. 4) while the leading edges 27 and 28 (beveled, as indicated, in the radial direction for sharpness) are advanced in the direction indicated by the arrows for insertion between the sucked-forward corners of the leading card and its successor. Fig. 9 illustrates the moment at which suction has drawn forward the upper corners 33 and 34 and the leading edges 27 and 28 are just about to be inserted. Immediately after insertion, the hoses 31 and 32 begin their return movement and the disks complete the separation as Fig. 10 indicates. As Fig. 10 further indicates, at this moment, a gap is provided between the hoses 31 and 32 at the stack 11 for the arrival of the segment 19 which is to pick up the separated leading card.

On the trailing edges of the segments 19 which rotate counterclockwise as seen in Figs. 1, 3, 5 and 7, are provided the shelf-like projections 35 for engaging the lower end of the leading card as it is separated from the stack and lifting the same along with the motion of the roller 15. In order to insure unfailing engagement of the lower edge of the leading card with these projections 35, there is provided a finger mechanism 36 best illustrated in the Figs. 3 and 5 and positioned just below the inner edges of the racks 13 and 14. This finger mechanism operates in timed relation to the separator disks 23 and 24, roller 15 and suction mechanisms 29 and 30 to press the lower edge of the leading card toward the segment 19 just prior to its engagement by the projections 35. The mechanism may be affixed to the bottom of the hopper 12 and comprises the cam-operated arm 37 journaled on the member 38 affixed to the hopper 12, the cam 39 rotatable in the direction shown, and the finger 40. The arm 37 is biased downwardly by the spring 41 while the finger 40 is biased to rotate in a clockwise direction by a suitable hair spring 42 at its journal with the arm 37. As seen, the finger 40 has a cam surface 43 for engagement with a cam stop 44 so that upward motion of the finger 40 caused by upward motion of the arm 37 will in turn cause the finger 40 to be rotated counterclockwise toward engagement with the lower edge of the leading card as illustrated in Fig. 5. Downward or counterclockwise rotation of the arm 37 will permit withdrawal of the finger 40 to the position shown in Fig. 3 by virtue of the spring

biasing. It will be apparent how the cam 39 operating on the cam roller 45 of the arm 37 will bring about this action when the cam is adjusted to provide the proper timing with relation to the separator disks and the segments 19. It is understood, of course, that the finger mechanisms are in duplicate—one co-operating with each separator disk as Fig. 4 illustrates.

As will be apparent from the Fig. 2, for example, the separator disks 23 and 24, together with the just-described finger mechanisms and their necessary operating mechanisms, are mounted on the guide racks 13 and 14 so that they may move therewith when adjustment is made for cards of different lengths. In order that the guide racks 13 and 14 may be adjusted toward and away from the center line for purposes of adjusting the machine to accommodate any given length of card, there may be provided the worm screw mechanisms 46 and 47 driven by the manually operable wheel 48 and the interconnecting belt 49. As will be readily understood, these mechanisms can be arranged to engage the guide racks 13 and 14 and move them in unison and in opposite directions toward and away from the center line of the hopper. Fig. 6 details a suitable construction in which the worm 46 engages the slide member 50 to move the same laterally of the hopper; the slide 50 in turn engaging the guide rack 14 through a suitable slot 51 in the supporting structure.

It is to be understood that any suitable means may be provided for causing the timed co-operation of the foregoing elements in the manner indicated, i. e., such that while the roller 15 rotates continuously the separator disks will feed the leading card of the stack 11 to a segment 19 in time to permit engagement of the projections 35 with the lower edge, the reciprocation of the suction mechanism at the proper time and the actuation of the fingers 40 at their proper time. However, a suitable means for powering the mechanisms in these timed relationships will now be indicated.

The prime mover of the machine may comprise the motor 52 (Fig. 1) driving the speed controlling gear box 53 which in turn drives through the belt 54, the roller 15, all of these mechanisms being fixedly mounted on the table-like structure 55. As Fig. 2 illustrates, the belt 54 applies power to the shaft 56 of the roller 15. Power from this shaft may then be transmitted through a suitable belt or chain drive illustrated by 57 to a main drive shaft 58 (Fig. 1). From the shaft 58 a similar belt or chain drive 59 may apply power to the shaft 60 upon which the cams 39 (Figs. 3 and 5) are mounted, thus providing the power for the finger mechanisms. Angular positioning of the cams 39 on this shaft 60, as is well understood, will permit adjustment of the necessary timing relationships. Further suitable belts or chain drives 61 may transmit power to a shaft 62 (Fig. 2) which supplies the motive power for the separator disks 23 and 24 through the beveled gear systems 63 mounted, as already indicated, by suitable means on the guide racks 13 and 14. The belts or chains 61 may be appropriately arranged to accommodate adjustment of the racks 13 and 14.

For reciprocating the suction mechanisms 29 and 30, there may be provided the belts or chain drives 64 which transmit power to the suitably mounted shafts 65 upon which are provided the eccentric cams 66 (Figs. 2 and 7). By mechanisms well understood, the cams 66 as they ro-

tate with their shafts may be caused to reciprocate the hoses 31 and 32 to cause them to approach the separator disks 23 and 24 at the proper moment and to withdraw therefrom in time to avoid the segments 19.

I claim:

1. In a machine for processing a stack of cards of the kind including a cylindrical pressure roller and cooperating cylinder between which the cards are successively passed with the relative rotation of the cylinder and roller, a mechanism for feeding the cards to the roller and cylinder comprising, a cylindrical pressure roller as aforesaid but including cut-out portions extending axially inwardly from its ends so as to form peripherally spaced segments on which the cards ride, a shelf device on the trailing edge of each of the segments for engaging the trailing edges of the cards, a rack for holding a stack of cards and directing them sequentially to the roller, a pair of separator disks for separating the leading card from the stack for pick-up by the roller and shelf device, reciprocating suction mechanisms for drawing the leading card into engagement with the disks movable through the cut-out portions into proximity with the separator disks, finger means for pushing the trailing edge of the leading card toward engagement with the roller to insure engagement thereof by the shelf device, and power means for driving the roller, the separator disks, the suction mechanisms, and the finger means in timed relation to position the cards successively on the segments.

2. In a machine for processing a stack of cards of the kind including a cylindrical pressure roller and co-operating cylinder between which the cards are successively passed with the relative rotation of the cylinder and roller, a mechanism for feeding the cards one by one to the roller and cylinder comprising, a cylindrical pressure roller as aforesaid but including cut-out portions extending axially inwardly from its ends so as to form peripherally spaced segments on which the cards ride, a shelf device on the trailing edge of each of the segments for engaging the trailing edges of the cards, a rack for holding a stack of cards and directing them sequentially to the roller including spaced parallel guides adjustable with respect to each other to accommodate different card lengths, a pair of separator disks each on one of the guides for separating the leading card from the stack for pick-up by the roller and shelf device, reciprocating suction mechanisms for drawing the leading card into engagement with the disks movable through the cut-out portions into proximity with the separator disks, finger means one on each of the guides for pushing the trailing edge of the leading card toward engagement with the roller to insure engagement thereof by the shelf device, and power means for driving the roller, the separator disks, the suction mechanisms and the finger means in timed relation to position the cards successively on the segments.

3. In a machine for processing a stack of cards of the kind including a cylindrical pressure

roller and co-operating cylinder between which the cards are successively passed with the relative rotation of the cylinder and roller, a mechanism for feeding the cards to the roller and

5 cylinder comprising a cylindrical pressure roller as aforesaid but including cut-out portions extending axially inwardly from its ends so as to form peripherally-spaced segments on which the cards ride, a shelf device on the trailing edge of each of the segments for engaging the trailing edges of the cards, a rack for holding a stack of cards and directing them sequentially to the roller, a pair of separator disks adjacent the outer surface of the pressure roller for separating the 10 leading card from the stack for pick-up by the roller and shelf device, reciprocatable suction mechanisms within the pressure roller for drawing the leading card into engagement with the disks movable through the cut-out portions into 15 proximity with the separator disks, means for moving the trailing edge of the leading card on the rack toward engagement with the roller to insure engagement thereof by the shelf device, and power means for driving the roller, the separator disks, and the suction mechanisms in timed relation to position the cards successively on the segments.

4. In a machine for processing a stack of cards of the kind including a cylindrical pressure roller and co-operating cylinder between which the cards are successively passed with the relative rotation of the cylinder and roller, a mechanism for feeding the cards to the roller and cylinder comprising a cylindrical pressure roller as aforesaid but including cut-out portions extending axially inwardly from its ends so as to form peripherally-spaced segments on which the cards ride, a shelf device on the trailing edge of each of the segments for engaging the trailing edges of the cards, a rack for holding a stack of cards and directing them sequentially to the roller including parallel-spaced guides adjustable with respect to each other to accommodate different card lengths, a pair of separator disks adjustable with the guides and adjacent the outer surface of the pressure roller for separating the leading card from the stack for pick-up by the roller and shelf device, reciprocatable suction mechanisms within the pressure roller for drawing the leading card into engagement with the disks movable through the cut-out portions into proximity with the separator disks, means for moving the trailing edge of the leading card on the rack toward engagement with the roller to insure engagement thereof by the shelf device, and power means for driving the roller, the separator disks, and the suction mechanisms in timed relation to position the cards successively on the segments.
